GORDON V. PLANTE, OF ATLANTA, GEORGIA, ASSIGNOR TO THE NATIONAL PAPER COMPANY, OF ATLANTA, GEORGIA

PAPER TUBE FORMING MACHINE

Application filed April 7, 1928. Serial No. 268,205.

This invention relates to improvements in paper tube forming or rolling machines.

An object of this invention is to construct a machine particularly adapted for forming or rolling paper tubes, in which there is provided means for revolving a winding spindle and stopping the rotation thereof at a predetermined point or position in the operation.

10 A further object of this invention is to provide a paper tube forming machine including a means for interrupting the reciprocating action and holding the spindle in a desired position during the winding process, 15 the apparatus being constructed in such a manner that the winding spindle and its supporting elements, when brought into a forward position, will remain stationary for a period of time, except for the rotation of 20 the winding spindle and its supporting shaft.

A further object of this invention is to provide a paper tube forming machine having a plurality of supporting members, a series of driving gearing positioned thereon adapted to operate a means for feeding a sheet of paper into the machine, a device for cutting off the paper at any desired length and for moving the paper from the point of cut off within operating distance 25 of the winding spindle, and suitable means for lifting and holding the paper against the winding spindle and wiping the overlapped portions of the paper firmly together, also means mounted upon a supporting member 30 for picking up the sheet of paper, preferably by a vacuum process, and a device whereby the roll and finished tube may be cut into sections of any desired length.

35 A prime object of this invention is to construct a paper tube forming machine having a suitable number of supporting members and driving gearing mounted thereon and timed and formed in such a manner that the revolving winding spindle will be given an 40 interrupted reciprocating motion whereby the spindle may be brought to its forward position and held automatically in that location while the paper roll is being formed, after which the spindle is brought automatically back to its retracted position, the tim-

ing and construction of the driving gearing being such that the functions of delivering the sheet of paper into the machine, cutting it off at proper length, moving the paper across a supporting member, bringing it in 55 operative relationship to the rotating spindle by means of a vacuum process or otherwise, wiping the overlapping edges of the paper firmly together and cutting off the paper tube to a desired length are all accomplished automatically. 60

Other objects of this invention will appear from the following detailed description of the device and as disclosed in the drawings, which are made a part of this application. 65

In the drawings—

Figure 1 illustrates a plan view of the paper tube forming machine disclosing the operative means for driving the spindle, interrupting its reciprocating action and the 70 various devices for handling the sheet of paper, all in assembled relationship.

Figure 2 illustrates a side elevational view of the machine, disclosing its various features in assembled and operative relationship at the 75 retracted position.

Figure 3 represents a front elevational view of the paper tube forming machine taken along line 3—3 of Figure 1.

Fig. 4 illustrates a vertical sectional view 80 of the tube forming machine taken along line 4—4 of Figure 1 and disclosing means for giving intermittent rotation to the winding spindle consisting of a system of mutilated gearing in combination with plate elements, 85 shown in this instance with the teeth of the gearing free from each other and the plates riding together.

Fig. 5 represents a fragmentary elevational view of Figure 4, disclosing primarily the 90 mutilated gearing and plate elements in position wherein the teeth of the gearing are in mesh.

Figure 6 illustrates a rear elevational view 95 of Figure 5, in which the mutilated gearing and cooperating plates are disclosed with the teeth free and the plates about to ride upon each other.

Figure 7 represents a rear elevational view 100 of Figure 5.

Fig. 8 illustrates a sectional side elevational view of a portion of the tube forming machine disclosing primarily the slotted cam member operatively positioned with respect to the crosshead guide and spindle shaft, the cam member being located at its retracted position.

Fig. 9 represents a sectional side elevational view of a portion of the tube forming machine, disclosing the slotted cam member at its extremely forward position in cooperative relationship with the spindle shaft.

Fig. 10 illustrates a sectional view of Figure 9 taken along line 10—10.

Fig. 11 illustrates a front elevational view of the tube forming machine, disclosing the various members assembled in operative relationship.

Fig. 12 illustrates a sectional view of the tube forming machine taken along line 12—12 of Figure 2, and disclosing particularly the guide or support member for holding one of the cutting knives in operative position.

Fig. 13 represents a sectional view taken along line 13—13 of Figure 12, disclosing primarily the upright guiding members for holding the movable knife member in operating position.

Fig. 14 represents a perspective view of the front edge of the table with the delivering rolls removed, and disclosing the cutting knives in operative position.

Fig. 15 illustrates a perspective view of the supporting plate for holding the movable knife in position, and attachable means for connecting an eccentric thereto, in such a manner that the knife blade may be given the desired movement.

Fig. 16 illustrates a vertical sectional view of a portion of the tube forming machine taken along line 16—16 in Figure 1, and disclosing means for automatically raising and lowering the fingers for holding the paper sheets in position after cutting and during the carrying forward movement of the sheets, the fingers in this instance being shown in raised position.

Fig. 17 illustrates a sectional view of a portion of the tube forming machine taken along line 17—17 of Figure 16 and clearly discloses the means by which the fingers are raised and lowered, consisting of a cam and lever movement.

Fig. 18 illustrates a vertical elevational view of the means for giving intermittent motion to the series of slides for carrying the paper forward.

Fig. 19 illustrates a view of Figure 18 taken along 19—19.

Fig. 20 represents a sectional view of Figure 16 taken along line 20—20, and particularly disclosing the ratchet construction within the cable drum member.

Fig. 21 illustrates a sectional view of Figure 28 taken along line 21—21, and discloses

the fingers and slides in forward position, the paper having been delivered between the spindle and the wiping plate, the wiping plate in this instance being disclosed in retracted position. This figure also discloses the adjustable means for cutting the paper tubes into lengths, the knife being disclosed in this instance free from the spindle and paper tube.

Fig. 22 represents a vertical sectional view of a portion of Figure 21, disclosing particularly the wiping plate under tension for the purpose of holding the paper properly against the spindle.

Fig. 23 illustrates a rear elevational view of the members for adjustably holding the tube cutting plates in position, the view being taken along line 23—23 of Figure 21.

Fig. 24 illustrates a vertical sectional view of a portion of Figure 21, disclosing the members in position for cutting the tube upon the spindle.

Fig. 25 illustrates a vertical sectional view of a portion of the tube forming machine disclosing the members in operative position for cutting the paper tube into lengths, and the cam means for actuating the movement of the cutting plates into that position.

Fig. 26 illustrates a bottom plan view of a portion of the tube forming machine disclosing the means for moving the tube cutting blades and the wiping plate.

Fig. 27 illustrates a side elevational view to an enlarged scale of the cam for moving the tube cutting blades into and out of operative position.

Fig. 28 represents a vertical sectional view of a portion of the tube forming machine taken along line 28—28 of Figure 21, and disclosing the cam and lever arrangement for operating the suction valve.

Fig. 29 illustrates a front elevational view of the cam for operating the suction valve, disclosing the cooperating cam element in position just previous to placing the suction valve in operation.

Fig. 30 represents a perspective view of the cam for operating the wiping plate, disclosing the structural members thereof in detached relationship.

Fig. 31 illustrates a longitudinal sectional view of the tube forming machine disclosing the winding spindle in operative relationship with the wiping plate, suction valve, and knife blades for cutting the paper tube.

Fig. 32 represents a longitudinal sectional view to an enlarged scale disclosing the suction valve in operative relationship with the winding spindle.

Fig. 33 illustrates a sectional view of Figure 32 taken along line 33—33.

Fig. 34 illustrates a diagrammatic view of a method for delivering paper properly supplied with adhesive to the feed rolls of the tube forming machine.

In the invention of a paper tube rolling machine herewith specified and claimed, it is preferred that numeral 1 designate a main base portion of the machine which may be made of any suitable material, such as cast iron, and adapted to have mounted therein a main driving shaft 2 and having keyed thereto a driving pulley 3, which may be operatively connected with any proper source of power, the driving shaft 2 being rotatably supported in part by the base portion 1, and bearing members 4, 5, and 6, which may be firmly attached to some suitable foundation. The driving power is transmitted through the pulley 3 and the main driving shaft 2, which has mounted on the inner end thereof a pinion member 7 enclosed by a housing 8, preferably integrally formed from the base portion 1 of the machine and having a cap portion 9 removably attached. The rotation of the pinion 7 functions to transmit power to a gear member 10, securely fastened to a shaft 11, which is preferably located above the main driving shaft 2 and held in rotative position by means of the upper sections 12, 13 and 14 of the supporting bearings for the main driving shaft 2. Crank member 15 is adapted to be securely keyed or otherwise to the shaft 11, and pivotally attached to the free end of the crank 15 is a sliding block member 16, which is adapted to cooperate with a slotted cam member 17 having a circular curved portion 18 and a groove or slotted section 19, one end of the cam 17 being pivotally mounted upon the base portion 1, as at 17', the upper end of the cam 17 being adapted to swing in cooperation with a cross head member 20, which functions to slide in a cylindrical cross head guide 21 supported by suitable bearing members 22 and 23 extending from the main body portion or base 1 of the machine. The free or swinging end of the cam 17 is preferably provided with a saddle fork construction 24 as clearly disclosed in the drawings, which functions to engage in slidable position therein suitable roller elements 25 and 26, which may be made of bronze, and are adapted to slip over pins 27 and 28 located in the crosshead 20 and securely held in position by means of plates 29 and 30, which may be screwed or otherwise in the ends of the pins.

Suitably mounted in the base portion 1 of the machine is a revolving spindle shaft 31, which is adapted to pass through cross head 20 within the cross head guide 21. The outer end of the revolving spindle shaft 31 may be mounted in a bearing extension 32 and extend a suitable distance there-beyond in order to accommodate a hardened collar portion 33, which is adapted to cooperate with a spring plunger element 34 held in position by means of a bracket 32' suitably fastened to the bearing extension 32; the spring plunger element 34, when pressed against the collar

33, tends to hold the spindle or revolving shaft in a steady position. Within the cross head guide 21 and at the forward end of the revolving spindle shaft 31 are adapted to be located collar portions 36 and 37 which will function to revolve with the rotating shaft 31. In this construction, the cross head 20 not only acts as a bearing for the rotating shaft 31, but also as a means for reciprocating the motion of the shaft. The forward end of the revolving spindle shaft 31 is adapted to be provided with a tapered recess (see Figure 32) 38, into which is adapted to be mounted the inner end of a tubular spindle 39 and held firmly in position therein by means of a screw collar portion 40. The spindle 39 may be easily removed by releasing the collar 40 and utilizing the hollow drift portion 41 located at the inner end of the spindle 39.

The operation of removing the spindle is similar to that in use with drill presses. The hollow or tubular spindle 39 is provided with a plurality of slots 42, longitudinally positioned therein at intervals along its length. The winding spindle 39 functions in a reciprocating motion within the cross head guide 21 and extends through a nose member 43 mounted in the guide head portion 44, which, together with guide head portion 45, is fastened to the cylinder cross head guide 21 by some suitable means, such as machine screws 46. The spindle shaft 31 is supported therefore by the guide head portion 44.

The action by which the revolving spindle or shaft 31 is made to rotate is preferably as follows:

The driving power is primarily transmitted from the driving shaft 2 through a gear 47 mounted thereon, which is adapted to cooperate with a gear 48 mounted upon a shaft 49, which is suitably supported at its ends by bearing members 50 and 51. A beveled pinion 52 is adapted to be securely fastened to the gear 48, the two members 48 and 52 are adapted to revolve freely upon the shaft 49, which is held stationary in its bearings 50 and 51. The gearing pinion 52 functions to impart rotation to a cooperating beveled gear 53, which is keyed to a shaft 54 rotating in bearings 55 and 56.

On the end of the shaft 56 is adapted to be keyed a mutilated toothed beveled gear 57 to which is fastened a plate 58. The beveled gear 57 engages with a pinion 59, to which is also attached a plate 60, the beveled gear 59 and plate 60 being mounted upon a shaft 61. The plates 58 and 60 are formed in such a manner as to remain in contact during a partial rotation of the beveled mutilated gear 57 and automatically releasing themselves when the mutilated face of gear 57 has passed and the teeth come in contact with the cooperating gear 59, thereby providing an intermittent motion to this particular point. The teeth in mutilated gear 57, coming in contact

with gear 59, will function to rotate the shaft 61 at an increased rate of speed owing to the fact that the beveled gear 59 is of a smaller diameter than the mutilated gear 57. The 5 beveled shaft 61 is supported by suitable bearing members 62 and 63.

A beveled pinion 64 is fixed at the end of shaft 61 and adapted to transmit power to a cooperating gear member 65, which, in turn, 10 is securely keyed or fixed to the lower end of a vertical shaft 66, at the upper end of which is fixed the beveled gear 67 adapted to mesh in operative relationship with a cooperating pinion 68, keyed to a shaft member 69, which, 15 is supported in suitable bearing elements 70, 71, and 72. The shaft 69 is adapted to extend a distance beyond the supporting element 72 in order to receive in fixed or keyed relationship thereon a silent chain sprocket wheel 73, 20 which is brought into operative relationship by means of a chain or other suitable driving element 74 with another sprocket wheel 75 mounted upon a shaft member 76 properly supported by bearings 77, 78, and 79 preferably extending in bracket form from the main base portion 1 of the machine. At a suitable position along the shaft 76 is mounted in keyed relationship thereto a gear 80 adapted to mesh with a driving cooperating gear member 81, which is securely fastened and mounted by means of a sliding key 82 to the revolving spindle shaft 31, thereby providing a means for revolving the winding spindle 39 and its supporting shaft 31. After the spindle shaft 31 has been moved forward to the desired position, the gear teeth in the mutilated gear 57 function to come in operative contact with the gear 59, thereby 35 providing rotary motion to the shaft 61, pinion 64, gear 65, vertical shaft 66, beveled gear and pinions 67 and 68, shaft 69, sprocket wheel 73, chain 74, sprocket 75, shaft 76, gear 80 to the gear 81, which is keyed to the revolving spindle shaft 31. The revolving 40 motion of the spindle and shaft will continue during a single revolution of the gear pinion 59, the diameter of which is carefully determined from the time it takes for the block 16 to travel through the slot 18 in the cam 17. 45 During the backward and forward movement of the winding spindle 39 and its supporting shaft 31, the rotation thereof is stopped by means of the mutilated gear 57 slipping out of mesh with the driving pinion 59. The 50 plates 58 and 60 function to hold the secondary drive, consisting of the beveled gear 59 in stationary position, so that, at the proper time, the mutilated gear 57 will come into positive relationship with the driving gear 59. The plates 58 and 60 are carefully designed and formed in order to cooperate in maintaining the mutilated gear 57 and the gear 59 in positive operative relationship with each other. The spring plunger member 55 65 64 is adapted to press against the hardened

collar elements 33, thereby functioning to hold the spindle shaft 31 in a forward position during this operation.

From Figure 2 of the drawings, it is apparent that the revolving action of the crank 15 through the sliding block 16 functions to bring the slotted cam 17 to a forward position, at which point the cam 17 will come to rest while the crank 15 continues its circular motion, the block 16 traveling around and 70 in the slot 18 from top to bottom thereof, the cam 17 remaining absolutely stationary during the predetermined period, as clearly disclosed in the drawings. The saddle fork 24 of the cam 17 is brought into operative relationship with the pins 27 and 28 located in the cross head 20. The identical movements which bring the cam 17 into a forward position function to carry the cross head 20 with the revolving shaft 31 attached thereto forward also, the parts mentioned remaining stationary except for the revolving of shaft 31 during the desired period of time, after which the block 16 makes a contact with the bottom of slot 19 and the cam 17 is then 75 thrown back to its starting point, the shaft 31, therefore, functioning with an interrupted reciprocating motion, which constitutes a prime object of this invention.

In the operation of feeding suitable paper or other material to the machine and forming it into a desired tube, it is preferred that the paper 83 be delivered upon a table portion 84 of the machine suitably supported on brackets 85 attached to the main base portion 1 of the apparatus by means of machine screws 86 or otherwise. The paper 83, in ordinary practice, is delivered to the machine from a roll of paper 103 mounted on an iron shaft 104, which is not a part of this invention, located in a convenient position to the tube forming machine and functioning as a source of supply for the paper 83 which passes, in ordinary practice, from the roll 103 between adhesive rolls 105 and 106, 80 positioned one above the other, the lower adhesive roll 106 being adapted to revolve in a receptacle 107 which contains an adhesive liquid. The paper 83 passing between the rolls 105 and 106 is properly spread with the 85 adhesive.

The paper 83 is then delivered to the table 84 by means of a pair of rolls 87 and 88. The paper is ordinarily guided by hand and delivered between the rolls 87 and 88, which 90 are mounted in bracket bearings 89 and 90 (see Figure 11), preferably connected in some proper manner to the table 84 of the machine. The lower roll 87 is preferred in this invention to be mounted in a fixed position in the bearings 89 and 90 while the upper roll 88 is mounted in adjustable sliding block members 91 (see Figure 28), which function to move in guide extensions 93 and 94, integrally a part of the bracket bearings 89 and 100 95 105 110 115 120 125 130

90. The upper or free ends of the guide elements 93, 94, are held in firm operative position by means of cap members 97 and 98 (see Figure 1), through which suitable tension or set screws 99 extend for cooperation with compression springs 101, which function to provide a means whereby a varying pressure may be exerted on the upper rolls for insuring a proper degree of friction necessary for pulling the paper on to the table 84 of the machine. This common form of tension device for paper feed rolls is used for adjusting the pressure of the upper roll 88 on the lower roll at each of the bearings 89 and 90. The upper and lower rolls 88 and 87 are mounted upon shafts or spindles 108 and 109. The lower shaft 109, passing through the roll 87, is adapted to have mounted thereon a spur gear 110, which is arranged to mesh with a similar gear 111, mounted upon shaft 108. The spindle 109 extends a suitable distance outwardly from the machine in order to accommodate a cable drum member 112, which functions to turn freely on the shaft 109. The drum member 112 is constructed having an open ended portion 113 for receiving a ratchet element 114, which is keyed in some proper manner to the lower roll shaft 109. The housing or open ended portion of the drum 113 is provided with a cap member 115 suitably fastened to the housing member 113 by means of machine screws 116 or otherwise. A series of dog members 117 are fastened to the cable drum 112 in a suitable manner and function to engage the teeth of the ratchet 114, thereby providing an action in which, by rotating the drum 112 in one direction, the lower roll 87 is made to revolve, the gear on the same shaft 110 imparting the same rotation to the upper roll, while a contrary movement will release the dogs 117 from the ratchet teeth 114, which will permit the drum 112 to rotate with a free action in the opposite direction. A cable or chain 118 passes around the drum 112 and connects with a shackle member 119, pivotally attached to an adjustable sliding block element 120 by means of a pin 121. The sliding block 120 is adapted to move in a fixed direction along a guiding portion 122 integrally a part of an arm member 123 having a longitudinal slot 124, in which is adapted to be slidably positioned a movable block 125 attached in a pivoted relationship to the free end of a crank arm member 126, which is properly mounted on a shaft 127, driven through suitable gearing 128 and 129, the gear 129 being mounted upon a shaft 130, which is, in turn, rotated by means of a suitable sprocket wheel 131 mounted thereon and connecting, by means of a chain drive 132 to a cooperating sprocket member 133 mounted upon a shaft 11. It is apparent that this arrangement of elements provides a movement wherein the rotation of the crank 126 will cause the arm member 123 to swing back and forth with a rapid motion backward and a slower motion forward, at the same time functioning to deliver or feed a proper amount of paper upon the table 84 for the purpose of forming a tube. As the arm member 123 swings backward, the cable 118 connecting it with the cable drum 112 is forced down by a weight 134 fastened to the lower end of the cable, the ratchet drum 114 functioning to spin freely. The reverse movement of the arm 123 causes the drum 112 to travel in the opposite direction when the dogs 117 engage the ratchet 114, functioning to turn the rolls and the sheet feeds into the machine between the knife members 135 and 136 and across the table. The sheet is then in position for cutting into the desired lengths and this is accomplished by means of a construction wherein the knife member 135 is adjustably bolted to the table portion 84 along an edge parallel with the rolls 87 and 88. The cooperating knife 136 is arranged to be supported by the standards 137 and 138 and in an upward and downward slidable relationship thereto, a movement which is brought about by means of a plate member 139 slidably positioned in upwardly extending guide portions 140 and 141, which may be an integral part of the supporting brackets, or fastened to the standard elements 137 and 138, or otherwise, the knife 136 being adjustably fastened to the plate 139 in a proper manner, so that its knife edge 142 will properly cooperate with the knife edge 143 of the member 135. The plate 139 is held in slidable operative position by means of a plate 144, which extends between the guiding elements 137 and 138, and securely fastened thereto by means of screws 145 and 146 (see Figure 12) or otherwise. The means for raising and lowering the plate 139, to which the knife blade 136 is attached, consists primarily of a pair of eccentrics 147 and 148 mounted upon a shaft or spindle 149, which is rotatably supported in the standards 137 and 138. The plate 139 is preferably detachably mounted in the eccentrics 147 and 148, as at 160, in such a manner that the rotation of the eccentrics will function to raise and lower the knife blade 136. The shaft 149 is operated from a cam 150, which is securely keyed or mounted on a shaft 151, supported in suitable brackets 152 and 153 attached in some suitable manner to the under portion of the table 84. The cam 150 is connected in operative relationship with the shaft 149 through a system of leverages consisting of a crank arm 154 mounted upon the shaft 149, the free end of which is pivotally attached to a crank link member 155 by means of a pin 156, the opposite end of the crank link 155 being pivotally connected, as at 157 to a crank member 158.

157, which cooperates with another crank member 158, both of the cranks being mounted upon the same spindle or shaft 159 in fixed relationship thereto. The spindle 159 is 5 adapted to be supported in some suitable manner from the table 84 by means of a bracket 162 extending therefrom. A rocker arm member 163 is slidably connected at one end to the crank 158 by means of a roller 10 164 which is adapted to be attached in some suitable manner to the free end of the crank 158 and adjusted to move within the slot 165 located in the rocker arm 163, the other end of the rocker arm 163 being supported in a 15 freely moving manner upon the shaft 127. The rocker arm 163 is provided, near its lower free end, with a roller element 166, which functions to extend inwardly and ride in the groove 167 of the cam 150, the shape 20 of the groove 167 being such as to impart upward and downward movement to the arm 163 when the shaft 151 is revolved, the up and down movement being transmitted through the cranks 158, 157, crank link 154 25 and crank 153 to the shaft 149, and, in turn transmitted to the knife 136, through the strap eccentric members 147 and 148 mounted upon the shaft 149. Any suitable means 30 may be utilized for operatively connecting the knife supporting plate 139 to the eccentrics 147 and 148.

As one modification of a means for accomplishing this purpose, suitable threaded lug extensions 168 and 169 are formed on the strap 35 portions 170 and 171 of the eccentrics, proper means being provided along the upper edge of the plate 139 for cooperating with the threaded lug portions in the eccentric strap members, thereby providing an efficient 40 means for imparting the desired up and down movement to the knife blade 136. In this connection, attention is called to the fact that the groove 167 in the cam 150 is so formed that, directly following the up and down motion 45 of the knife blade 136, there is a distinct pause between the movements, thus permitting the removing of one sheet of paper out of the way and bringing another sheet across the table. The cam 150, being mounted upon the shaft 50 151, is driven by means of a sprocket wheel 172 keyed thereon and adapted to cooperate with a driving chain 173, which, in turn, meshes with the sprocket wheel 174 mounted on the shaft 11, which is driven in turn from 55 the main shaft 2.

The mechanism above described will function to feed the paper into the machine onto the table 84 and cut the material into proper size for further operation. In order to move 60 the paper into cooperative relationship with the winding spindle 39, it is preferred, as one modification of this invention, to provide a series of slides 175, 176, and 177 suitably mounted in the top 178 of the table 84 in such 65 a manner that the upper surfaces of the slides

will be flush with the table top. The slides 175, 176, and 177 are operated preferably by an intermittent crank and link movement, which functions as follows:

A beveled pinion 178 is keyed to shaft 127 70 in a desired position for meshing with the cooperative beveled gear 179 keyed to a vertical shaft 180, which is suitably mounted and supported on a bracket portion 181 extending from a section of the machine. The shaft 127 is rotatably mounted in suitable bearings 182 and 183. The upper end of the vertical shaft 180 is preferably provided with a fixed mutilated tooth beveled gear 184 and having attached thereto a stop plate 185, the mutilated gear 184 being adapted to mesh at a predetermined time with a pinion 186 and a cooperating plate 187 mounted upon a spindle or shaft 188, which is, in turn supported by suitable bracket or bearing portions 189. On the shaft or spindle 188 is adapted to be keyed a crank 190, to which is pivotally connected, as at 191, a connecting rod 192, which in turn connects in a pivoted manner, as by pivot 193 with an oscillating lever member 194, which is keyed to a shaft 195 suitably mounted in bracket or standard sections 196 and 197 attached to a portion of the machine. A lever 198 is mounted in fixed relationship on the shaft 195 and is adapted to have pivotally 80 connected to its free end, as at 199 (see Figure 21), a link member 200, which is mounted at one end on a shaft 201. The shaft 201 is suitably mounted on bearings 202, 203 and 204, which are supported or attached in a proper 85 manner to the slides 175, 176 and 177. It is apparent from this arrangement of members that the rotation of the crank 190 will function to rock the lever arm 194, thereby causing the slides 175, 176 and 177 to move back and forth with an intermittent motion. 90

Properly keyed to the shaft 127 is a cam member 205, which functions to operate a lever 206 mounted upon a spindle 207, which is carried in bearing or bracket portions 208 and 209 fastened to a portion of the machine. A lever element 210 is mounted upon the spindle or shaft 207 and is of such a length that it will lift and drop through the action of cam 205, a rod member 211, which is securely 100 clamped to an extension of the shaft 201 by means of a clamping element 212. A pair of suitably formed fingers 213 and 214 are securely fastened at one end to the shaft 201, the outer or free ends of the fingers are provided with contacting members 217 and 218 105 (see Figure 17). The construction described functions to automatically raise and lower the fingers 213 and 214 in such a manner as to permit the paper sheets to pass under the contact portions 217 and 218 and then to drop and hold the sheet in position after cutting and continuing the carrying forward movement of the slides 175, 176, and 177. 110

In order to wipe the overlapping edges 115

of the paper tube firmly together and as one means for accomplishing this purpose, it is preferred to provide a wiper plate 219, which is fastened to supporting members 220, pivotally attached to bracket portions 221, which are fastened to the table 84. The supporting member 220 for the wiper plate 219 is arranged and constructed in such a manner that one end, as at 222, will function to operate with a proper revolving cam 223 mounted upon the shaft 151, the portion 222 may be provided with a roll 224 for cooperating with the cam 223, thereby providing a means for causing the wiping plate 219 to rise and fall at predetermined intervals, in order to wipe the overlapping edges of the paper firmly together before removing the tube from the winding spindle 39.

The cam member 223 may be constructed of any suitable material and is adapted to be provided with openings 225 suitably spaced around the periphery and arranged in such a manner that a cooperating member 226 may be adjustably attached to the main body portion 223 of the cam by means of machine bolts 227, thereby providing a cam device which may be adjusted for the proper operation of the wiping plate 219. In order to provide a proper tension to the wiping plate 219, a suitably formed spring element 228 is arranged to cooperate with the pivoted arm member 220 and the bracket portion 221.

It is preferred in this invention to provide means for cutting the tube into desired lengths before the article is withdrawn from the spindle, wherein the numeral 229 designates an adjustable sliding plate properly positioned upon an extension of the table member 84, as clearly disclosed in Figure 21 of the drawings. The adjustable plate 229 may be made of any suitable material such as cast iron, and is adapted to be moved back and forth at pre-determined intervals by a cam member 230 mounted in fixed relationship upon the shaft 151, and located beneath the sliding plate 229. In order to operatively connect the cam 230 to the sliding member 229, it is preferred in this invention to provide an opening 231 in the table portion 84 through which is adapted to extend a sliding block element 232 securely fastened to the plate member 229, the main portion of the sliding block 232 being adapted to ride in a specially formed groove 233 in the cam member 230, in such a manner that when the shaft 151 revolves the plate 229 will move back and forth a distance equal to the stroke of the sliding member in the groove.

Adjustably mounted upon the sliding plate member 229 is a guiding bracket 234, arranged to receive in slidable relationship thereto a series of dovetailed sliding blocks 235, adjustably arranged to carry a series of knife blades 236.

The guiding bracket 234 is provided with openings 237 through which suitable tension bolts 238 extend in such a manner that an advanced or retarded adjustment may be given to the guiding plate 234 in relationship to the sliding plate 229. The sliding block members 235 are provided with lateral adjustment, each of the blocks being preferably made in two portions, the forward portion 238 being dovetailed into the rear portion 235, and held in operative relationship by means of a screw 239 capable of vertical adjustment to suit requirements.

Each of the forward portions 238 of the sliding block 235 is formed having a groove 240 in which the knife blades 236 may be adjustably positioned.

The sliding block members 235 are adapted to be held in any desired lateral adjustment by means of a set screw 241.

Attached to the table portion 84 is a bracket element 242 for the purpose of adjustably supporting a set screw 243 attached to hold the guiding bracket 234 in a desired position.

After the knife 136 has descended and cut the sheet into the desired size, the fingers 213 and 214 are descended and hold the severed sheet firmly against the slides 175, 176, and 177, the knife 136 having in the meantime returned to its normal position out of contact with the paper. The slides then begin to move forward carrying the sheet of paper clearly designated in Figure 1 by the numeral 244, the sheet stopping with the edge of the paper at a point just beyond the center of and beneath the winding spindle 39, which has meanwhile moved forward simultaneously with the forward movement of the slides. At this instant the wiping plate 219 rises lifting the edge of the paper 244 and pressing it against the slotted portions 42 in the spindle 39, and cam member 245 mounted in fixed relationship on shaft 151 is adapted to actuate an intake valve 246 through a series of levers 247 and contact elements 248.

The intake valve 246 is opened connecting the valve with a vacuum tank which functions to produce a suction effect within the hollow portion 249 of the spindle 39, and functions to retain the paper firmly against the slotted portions 42 in the spindle.

Figure 32 clearly discloses the relationship within the valve 246 and the spindle 39 at the time the spindle is in position for receiving the paper sheet previous to winding. The spindle having received the sheet of paper, as above described, begins to revolve thereby winding the sheet into a tube, the wiping plate 219 functioning to press the laps of the tube firmly together and sealing down the edges, drop out of the way at the end of the operation.

The machine members, according to this invention, are so arranged that when the wip-

ing process has been completed, the guiding bracket 240 carrying the knives 236, functions to come forward and cut the tube into desired lengths.

5. As the knives are withdrawn the spindle ceases to revolve and swings back, stripping the tubes therefrom in the act and a fresh sheet of paper is now brought forward into position for another tube.

10. In operation this invention provides a paper tube forming machine in which the paper may be delivered by hand or other suitable means through the rolls and beneath the upraised knife, power is then applied, the 15 preliminary cut is made and the machine then functions completely once without rolling the tube because there is nothing to roll.

Beginning at the point of the rolls the paper is delivered a full length sheet across 20 the table beneath the proper members for carrying the sheet forward. At the desired position the sheet is cut off by the action of the knife and the members for carrying the sheet forward come into operation, and 25 thence advance the sheet to a position beneath the winding spindle, which meanwhile has advanced to the required position; an additional member then comes into operation lifting the sheet and pressing it firmly against 30 the lateral slots in the winding spindle, aided by vacuum means, after which the spindle begins to revolve and the tube is wound.

35. A successive number of movements are provided at this point, not only to wind the tube but to press the laps or convolutions of the tube firmly together. Simultaneously with the beginning of the winding spindle revolutions, the members which have carried the sheet forward, release themselves automatically and free the paper for the winding 40 operation.

Following the winding of the main tube, a series of mechanisms carrying a number of cutting or trimming knives move to the 45 desired position and sever the tube into sections of desired length. The cutting members then withdraw automatically and the winding spindle ceases to revolve, at the same time starting a backward movement 50 which brings the tube sections against a nose block element thereby preventing their further movement and stripping them from the spindle.

55. It is understood that changes and alterations may be made in the above disclosure both in the specifications and drawings within the scope of the appended claims without in any manner affecting the merits of this invention.

60. What I claim is:

1. In a paper tube forming machine, a reciprocating spindle mounted therein, means for revolving and stopping the rotation of the spindle at a predetermined period, means 65 for feeding a sheet of paper into the ma-

chine, means for cutting the sheet of paper into the desired lengths, means for moving the sheet of paper, from the point of cut off to a desired position under the spindle, means for lifting and winding the sheet of paper around the spindle, with its edges overlapping, means for wiping the overlapping edges firmly together and means for cutting the tube into desired lengths and means for forcing the tube from the spindle on the retraction of said spindle. 70 75

2. In a paper tube forming machine having a reciprocating winding spindle, a crank member mounted upon a suitable driving shaft, a sliding block element attached to the free end of the crank, a cam member pivotally mounted at one end on a suitable portion of the machine, a slotted section in the cam for receiving the sliding block element, a saddle fork in the free end of the cam member, a cross head element for holding the winding spindle in position, means on the cross head for cooperating with the saddle fork of the cam and bringing the free end of the cam into a forward position, together with the cross head and revolving winding spindle, the cam, cross head and spindle remaining stationary except for the revolving of the spindle during a period of time. 80 85 90

3. In a paper tube forming machine having a reciprocating winding spindle, a mutilated gear and pinion for revolving and stopping the rotation of the spindle at a desired position, guide plates fastened to the mutilated gear and pinion in such a manner that they will function to remain in contact during a partial rotation of the mutilated gear and automatically release themselves when the mutilated portion of the gear has passed and again cooperates with the pinion, thereby providing intermittent rotative motion to the winding spindle. 95 100 105

4. In a paper tube forming machine having a reciprocating winding spindle, means for delivering a sheet of paper to the machine for forming into a tube, means for moving the paper into cooperative relationship with the winding spindle, means for giving intermittent motion to the movement of the paper, vacuum means for bringing the paper into firm contact with the spindle, means for cutting the tube into desired lengths, and means for forcing the tube from the spindle on the retraction thereof. 110 115 120

In testimony whereof I affix my signature. 120
GORDON V. PLANTE.
